(57) **CLAIM**

We claim the ornamental design for a cutter, as shown and described.

DESCRIPTION

FIG. 1 is a view of one side of a cutter.

FIG. 2 is a view of the other side the cutter of FIG. 1.

FIG. 3 is a front view of the cutter of FIG. 1.

FIG. 4 is a rear view of the cutter of FIG. 1.

FIG. 5 is a bottom view of the cutter of FIG. 1.

FIG. 6 is a top view of the cutter of FIG. 1.

FIG. 7 is a front bottom perspective view of the cutter of FIG. 1.

FIG. 8 is a front top perspective view of the cutter of FIG. 1.

FIG. 9 is a rear top perspective view of the cutter of FIG. 1.

FIG. 10 is a rear bottom perspective view of the cutter FIG. 1.

FIG. 11 is a front perspective view of the cutter of FIG. 1.

FIG. 12 is a rear perspective view of the cutter of FIG. 1.

FIG. 13 is a top perspective view of the cutter of FIG. 1.

FIG. 14 is a bottom perspective view of the cutter of FIG. 1.

FIG. 15 is a view of one side of an alternative construction of a cutter.

FIG. 16 is a view of the other side the cutter of FIG. 15.

FIG. 17 is a front view of the cutter of FIG. 15.

FIG. 18 is a rear view of the cutter of FIG. 15.

FIG. 19 is a bottom view of the cutter of FIG. 15.

FIG. 20 is a top view of the cutter of FIG. 15.

FIG. 21 is a front bottom perspective view of the cutter of FIG. 15.

FIG. 22 is a front top perspective view of the cutter of FIG. 15.

FIG. 23 is a rear top perspective view of the cutter of FIG. 15.

FIG. 24 is a rear bottom perspective view of the cutter FIG. 15.

FIG. 25 is a front perspective view of the cutter of FIG. 15.

(Continued)

FIG. 26 is a rear perspective view of the cutter of FIG. 15. FIG. 27 is a top perspective view of the cutter of FIG. 15. FIG. 28 is a bottom perspective view of the cutter of FIG. 15. FIG. 29 is a view of one side of another alternative construction of a cutter. FIG. 30 is a view of the other side the cutter of FIG. 29. FIG. 31 is a front view of the cutter of FIG. 29. FIG. 32 is a rear view of the cutter of FIG. 29. FIG. 33 is a bottom view of the cutter of FIG. 29. FIG. 34 is a top view of the cutter of FIG. 29. FIG. 35 is a front bottom perspective view of the cutter of FIG. 29. FIG. 36 is a front top perspective view of the cutter of FIG. 29. FIG. 37 is a rear top perspective view of the cutter of FIG. 29. FIG. 38 is a rear bottom perspective view of the cutter FIG. 29. FIG. 39 is a front perspective view of the cutter of FIG. 29. FIG. 40 is a rear perspective view of the cutter of FIG. 29. FIG. 41 is a top perspective view of the cutter of FIG. 29; and, FIG. 42 is a bottom perspective view of the cutter of FIG. 29. The broken lines in the figures represent portions of the cutter that form no part of the claimed design.
